UNITED STATES PATENT OFFICE

CHARLES C. SUNDERLAND, OF NEW BRUNSWICK, NEW JERSEY, ASSIGNOR TO JOHN A. ROEBLING'S SONS COMPANY, OF TRENTON, NEW JERSEY, A CORPORATION OF NEW JERSEY

BRIDGE CABLE SPINNING APPARATUS

Application filed January 30, 1931. Serial No. 512,458.

This invention relates to cable spinning apparatus such as used in spinning parallel bridge cables, the object of the invention being to provide a more efficient guiding of the 5 spinning wheel in passing guiding sheaves and a more efficient control of the guiding sheaves and traction rope and by which a higher spinning speed is made practicable.

In accordance with the present invention, 10 the guiding sheaves on which the spinning wheel traction rope runs for support and guidance through the span are mounted to swing sidewise and preferably supplied with guiding members coacting with the spinning 15 wheel carrier to assure the proper position of the guiding sheaves relatively to the traction rope and spinning wheel carrier in case of sway of the traction rope or carrier. The spinning wheel carrier, also, is preferably 20 mounted to swing freely sidewise on the traction rope so that the swinging of the carrier aids in assuring its proper position in passing the guiding sheaves. The upper guiding sheaves, also, are preferably mounted to rock 25 longitudinally of the traction rope so as to maintain their proper position and equalize the rope pressure on the sheaves.

For a full understanding of the invention, 30 a detailed description of constructions of preferred forms embodying the invention will now be given in connection with the accompanying drawings forming a part of this specification and the features forming the invention then specifically pointed out in the 35 claims.

In the drawings:

Figure 1 is a sectional elevation of a traction rope and guiding sheave construction 40 without the rocking feature of the upper sheaves, the section being taken transversely to the traction rope;

Figure 2 is an enlarged cross section on the line 2 of Figure 1;

Figure 3 is a sectional elevation on an enlarged scale looking to the left in Figure 1;

Figure 4 is a view similar to Figure 1 with the upper sheaves mounted to rock on the sheave support;

Figure 5 is a sectional side elevation of Figure 4.

Referring to the drawings, A is the carrier frame for the spinning wheel, shown as carrying two spinning wheels B, B', but it will be understood that either a single spinning wheel or more than two spinning wheels may be carried by frame A. C is the traction rope on which the spinning wheel carrier is mounted to swing freely, as described hereafter. D, D' are lower guiding sheaves, on which the traction rope runs and E, E' the usual guiding sheaves above the traction rope. All the set of guiding sheaves D, D' and E, E' are shown as mounted on a supporting frame F securely mounted on a bent G, which may be one of the bents from which the tramway used in laying the cable is supported. The frame F may be of any suitable construction, but is shown as a skeleton frame formed of angle bars for strength.

The frame A carrying the spinning wheel or wheels B, is shown as a skeleton metal frame and is supported from the traction rope C so as to swing freely thereon while being driven thereby, and to accommodate itself to bends in the traction rope and permit accurate adjustment longitudinally of the traction rope as follows: Frame A is carried at the end by links 10 from end supports 11, a series of holes 1 for connection of these links at different points longitudinally of the traction rope for adjustment being shown, and these end supports 11 are swung from the traction rope by arms 2 having at their ends sleeves 3, preferably split for convenience of application to the traction rope, which sleeves are loose on the traction rope so as to swing freely thereon. Intermediate of the end supports 11, the frame A is supported from the traction rope by support 12 having a vertical slot and pin connection 4 to the frame A so as to permit of vertical movement of the frame on bending of the traction rope and this support 12 is swung on the traction rope by arms 5 carrying sleeves 3 on the traction rope, similar to the sleeves 3, by which support 11 is mounted thereon. The frame A is driven by the traction rope through one or more sleeves 6 secured to the traction rope with a series of loose filling sleeves 7 between the support sleeves 3 and the driving sleeves 6. At the 100

end of the spinning wheel carrier mounting on the traction rope, conical sleeves 8, preferably of elastic material, are used to provide for the carrier mounting entering readily the space between guide sheaves and to prevent shock.

The lower guide sheaves D, D', on which the traction rope runs, are mounted to rotate freely in V-shaped bracket 14 pivotally mounted on stud 15 to swing sidewise in arms 9 forming part of the frame F, and these sheaves D, D', as shown, are inclined downward and outward away from the spinning wheel carrier, so as to allow the latter to pass freely between the sheaves. The upper sheaves E, E', also, are carried by the swinging bracket 14, being mounted thereon by arms 13 on brackets 18 bolted to bracket 14 by bolts 19. Each of the sheaves D, D' preferably carries guides 16 extending forward and rearward from the inner surface of the sheaves at their axes, these cam guides 16 preferably being formed, as shown, of a metal plate passing over the inner surface of the sheaves and inclined outward at both sides of the sheaves to form the guides 16 and carried by and secured at its ends to the bracket 14. The guides 16, also, preferably are supported at the center of the plate forming them by being secured to the ends of the studs 17 in the brackets 14 in which the sheaves D, D' are mounted to rotate.

The inclined or cam portions of the guides 16 are positioned to be engaged by a support 35 11 of the spinning wheel carrier on movement of the carrier in either direction in case the carrier frame is swung in its travel out of line with the traction rope or the guiding sheaves are swung sidewise with the traction rope 40 relatively to the spinning wheel, and thus the bracket 14 with the guiding sheaves and the spinning wheel carrier and spinning wheel will be brought into proper relative position for the spinning wheel carrier to pass between the sheaves D, D'. These guides may be omitted and contact of the wheel carrier with the sheaves or gravity relied on to position the parts.

The construction shown in Figures 4 and 5 is the same as that shown in Figures 1-3 and above described, except that the upper guide sheaves E, E' are mounted to rotate on a rocking carrier 20 formed of side bars straddling the traction rope and lower guide 55 sheaves and pivotally mounted on studs 21 in the opposite arms of the bracket 14. The upper guide sheaves E, E' thus rock with any bending of the traction rope C from the position shown in full lines in Figure 5 to that 60 shown in dotted lines so as to maintain their bearing on the traction rope under equal pressure, in addition to swinging with the traction rope as in the construction shown in Figures 1-3.

65 It will be understood that the swinging

mounting of the guiding sheaves and the guides coacting with the spinning wheel carrier may be used with a spinning wheel not having the swinging mounting on the traction rope, but preferably both the guiding sheaves 70 and the spinning wheel frame will be mounted to swing, as shown and described herein. The inclined guide sheaves and mounting of the spinning wheel carrier forms no part of the present invention except in combination 75 with the guide sheave mounting but in themselves form the subject matter of a separate application.

It will be understood that the invention is not limited to the particular form or arrangement of devices shown, but that many modifications may be made therein while retaining the invention as defined by the claims.

What I claim is:

1. In a cable spinning apparatus, the combination with the traction rope, of a spinning wheel, a spinning wheel carrier, and guide sheaves for the traction rope mounted to swing sidewise for relatively positioning the sheaves and carrier. 85

2. In a cable spinning apparatus, the combination with the traction rope, of a spinning wheel, a spinning wheel carrier, guide sheaves for the traction rope mounted to swing sidewise, and guiding devices coacting 95 with the spinning wheel carrier and sheave mounting for relatively positioning the sheaves and carrier.

3. In a cable spinning apparatus, the combination with the traction rope, of a spinning wheel, a spinning wheel carrier mounted to swing on the traction rope, and guide sheaves for the traction rope mounted to swing sidewise with the traction rope for relatively positioning the sheaves and carrier. 100

4. In a cable spinning apparatus, the combination with the traction rope, of a spinning wheel, a spinning wheel carrier mounted to swing on the traction rope, guide sheaves for the traction rope mounted to swing sidewise with the traction rope, and guiding devices coacting with the spinning wheel carrier and sheave mounting for relatively positioning the sheaves and carrier. 110

5. In a cable spinning apparatus, the combination with the traction rope, of a spinning wheel, a spinning wheel carrier, carrier supporting devices mounted on the traction rope and extending downward vertically in line with the traction rope, guide sheaves below the traction rope on opposite sides of the traction rope and carrier, said sheaves being separated and inclined downward and outward from the traction rope to provide space 120 for the passage of the wheel carrier between them, and a support for said guide sheaves mounted to swing with the traction rope. 125

6. In a cable spinning apparatus, the combination with the traction rope, of a spinning wheel, a spinning wheel carrier, carrier sup- 130

porting devices mounted on the traction rope and extending downward vertically in line with the traction rope, guide sheaves below the traction rope on opposite sides of the traction rope and carrier, said sheaves being separated and inclined downward and outward from the traction rope to provide space for the passage of the wheel carrier between them, a support for said guide sheaves mounted to swing with the traction rope, and guiding devices coacting with the spinning wheel carrier and sheave mounting for relatively positioning the sheaves and carrier.

7. In a cable spinning apparatus, the combination with the traction rope, of a spinning wheel, a spinning wheel carrier frame carrying said wheel, carrier supporting devices mounted to swing on the traction rope and extending downward vertically in line with the traction rope, guide sheaves below the traction rope on opposite sides of the traction rope and carrier supporting devices, said sheaves being separated and inclined downward and outward from the traction rope to provide space for the passage of the carrier between them, and a support for said guide sheaves mounted to swing with the traction rope.

8. In a cable spinning apparatus, the combination with the traction rope, of a spinning wheel, a spinning wheel carrier, carrier supporting devices mounted on the traction rope and extending downward vertically in line with the traction rope, guide sheaves below the traction rope on opposite sides of the traction rope and carrier, said sheaves being separated and inclined downward and outward from the traction rope to provide space for the passage of the wheel carrier between them, a support for said guide sheaves mounted to swing with the traction rope, and guiding devices coacting with the spinning wheel carrier and sheave mounting for relatively positioning the spinning wheel and sheaves.

45 9. In a cable spinning apparatus, the combination with the traction rope, of a spinning wheel, a spinning wheel carrier, carrier supporting devices mounted on the traction rope and extending downward vertically in line with the traction rope, guide sheaves below the traction rope on opposite sides of the traction rope and carrier, said sheaves being separated and inclined downward and outward from the traction rope to provide space for the passage of the wheel carrier between them, a support for said guide sheaves mounted to swing with the traction rope, and cam guides carried by the sheave mounting and extending forward and rearward of the sheaves in position to be engaged by the spinning wheel carrier for relatively positioning the spinning wheel and sheaves.

60 10. In a cable spinning apparatus, the combination with the traction rope, of a spinning wheel, a spinning wheel carrier, a plurality

of guide sheaves above the traction rope mounted to swing sidewise with the traction rope, and a carrier for said guide sheaves mounted to rock longitudinally of the traction rope, said guide sheaves being mounted in said carrier on opposite sides of its pivot to move in opposite directions with the traction rope.

11. In a cable spinning apparatus, the combination with the traction rope, of a spinning wheel, a spinning wheel carrier, a plurality of guide sheaves above the traction rope and a carrier for said guide sheaves mounted to rock longitudinally of the traction rope, said guide sheaves being mounted in said carrier on opposite sides of its pivot to move in opposite directions with the traction rope.

12. In a cable spinning apparatus, the combination with the traction rope, of a spinning wheel, a spinning wheel carrier, carrier supporting devices mounted on the traction rope and extending downward vertically in line with the traction rope, guide sheaves below the traction rope on opposite sides of the traction rope and carrier, said sheaves being separated and inclined downward and outward from the traction rope to provide space for the passage of the wheel carrier between them, a support for said guide sheaves mounted to swing with the traction rope, a plurality of guide sheaves above the traction rope mounted to swing sidewise with the traction rope, and a carrier for said guide sheaves mounted to rock longitudinally of the traction rope, said guide sheaves being mounted in said carrier on opposite sides of its pivot to move in opposite directions with the traction rope.

13. In a cable spinning apparatus, the combination with the traction rope, of a spinning wheel, a spinning wheel carrier, carrier supporting devices mounted on the traction rope and extending downward vertically in line with the traction rope, guide sheaves below the traction rope on opposite sides of the traction rope and carrier, said sheaves being separated and inclined downward and outward from the traction rope to provide space for the passage of the wheel carrier between them, a support for said guide sheaves mounted to swing with the traction rope, a plurality of guide sheaves above the traction rope and a carrier for said guide sheaves mounted to rock longitudinally of the traction rope, said guide sheaves being mounted in said carrier on opposite sides of its pivot to move in opposite directions with the traction rope.

14. In a cable spinning apparatus, the combination with the traction rope, of swinging bracket 14, guide sheaves D, D' mounted in said bracket below the rope and inclined outward and downward, and a spinning wheel carried on said rope between said sheaves.

15. In a cable spinning apparatus, the

combination with the traction rope, of swinging bracket 14, guide sheaves D, D' mounted in said bracket below the rope and inclined outward and downward, and a spinning wheel 5 carried on said rope, and mounted to swing sidewise thereon between said sheaves.

16. In a cable spinning apparatus, the combination with the traction rope, of swinging bracket 14, guide sheaves D, D' mounted 10 in said bracket below the rope and inclined outward and downward, a spinning wheel carried on said rope between said sheaves, and guide sheaves E, E' mounted in said bracket above the traction rope.
- 15 17. In a cable spinning apparatus, the combination with the traction rope, of swinging bracket 14, guide sheaves D, D' mounted in said bracket below the rope and inclined outward and downward, a spinning wheel 20 carried on said rope and mounted to swing sidewise thereon between said sheaves, and guide sheaves E, E' mounted in said bracket above the traction rope.

18. In a cable spinning apparatus, the combination with the traction rope, of swinging bracket 14, guide sheaves D, D' mounted 25 in said bracket below the rope and inclined outward and downward, a spinning wheel carried on said rope between said sheaves, 30 rocking carrier 20 pivoted on said bracket to rock longitudinally of the traction rope, and upper guide sheaves E, E' mounted on said carrier on opposite sides of the carrier pivot.

19. In a cable spinning apparatus, the combination with the traction rope, of swinging bracket 14, guide sheaves D, D' mounted in said bracket below the rope and inclined outward and downward, a spinning wheel 40 carried on said rope and mounted to swing sidewise thereon between said sheaves, rocking carrier 20 pivoted on said bracket to rock longitudinally of the traction rope, and upper guide sheaves E, E' mounted on said carrier 45 on opposite sides of the carrier pivot.

In testimony whereof, I have hereunto set my hand.

CHARLES C. SUNDERLAND.
